UNITED STATES PATENT OFFICE.

ELMER E. GORRINGE, OF SALT LAKE CITY, UTAH.

PROTECTOR.

1,181,521.

Specification of Letters Patent.

Patented May 2, 1916.

Application filed February 12, 1915. Serial No. 7,784.

To all whom it may concern:

Be it known that I, ELMER E. GORRINGE, a citizen of the United States, residing at Salt Lake City, in the county of Salt Lake 5 and State of Utah, have invented new and useful Improvements in Protectors, of which the following is a specification.

This invention relates to protectors and the object of the invention is to provide a 10 simple and inexpensive device which may be placed beneath the buttons of a shoe for preventing pinching of the foot or drawing the stocking into the button hole when the shoes are being buttoned.

Another object of the invention is to provide a device of this character which may be 15 conveniently applied and removed after the shoes are buttoned and which is provided with means for the insertion of a button hook to facilitate the removal.

Further objects of the invention will appear as the following description is read in 20 connection with the accompanying drawing, which forms a part of this application, and in which:—

Figure 1 is a perspective view with parts broken away showing the application of the device. Fig. 2 is a perspective view of the 25 device removed.

In the specific embodiment of the invention 30 as illustrated herein, the device comprises a single piece of material such as celluloid or any other suitable material, which

is sufficiently flexible to conform to the outline of the foot. The device is generally indicated at 1 and has the outline of an irregular arc and gradually tapers from one end to the other, as shown. At the wide end 35 an aperture 2 is formed to permit withdrawal of the device by means of a button hook and this aperture is reinforced preferably by a metallic gromet or other similar device.

In practice, the device is placed beneath the buttons on the shoe upper and the button hook is then hooked into the eyelet and the device removed. By employing a device of this character the buttoning of the 40 shoe is not only facilitated but the device prevents the stocking from being drawn 45 into the button hole and also eliminates pinching.

What is claimed is:—

In combination with a button shoe, a 50 flexible member bent longitudinally to conform to the curvature of the row of buttons upon the shoe and adapted to be placed beneath the buttons between the shoe and the foot when buttoning the shoe.

In testimony whereof I affix my signature 55 in presence of two witnesses.

ELMER E. GORRINGE.
